UNITED STATES PATENT OFFICE.

ELMER E. GOAR, OF STEPHEN, MINNESOTA.

HARNESS-HANGER.

1,113,001.

Specification of Letters Patent.

Patented Oct. 6, 1914.

Application filed January 20, 1914. Serial No. 813,285.

To all whom it may concern:

Be it known that I, ELMER E. GOAR, a citizen of the United States, residing at Stephen, in the county of Marshall and State of Minnesota, have invented new and useful Improvements in Harness-Hangers, of which the following is a specification.

This invention relates to harness hangers from which the harness may be supported in suspended position when not in use.

To this end the invention essentially consists of relatively movable separable arms for supporting the harness and having their free ends detachably connected to permit the harness to be attached thereto and removed therefrom when desired.

The primary object of the invention is the provision of a device of this character whereby the arms may be readily and easily disengaged to a release of the harness, and automatically interlocked when moved into operative or supporting position.

I further aim to provide a connection between the arms to insure the same from being casually moved to released position by any lateral pressure brought to bear against the sides thereof.

It is a further object of the invention to provide a device of the above mentioned character with means for limiting the movement of the arms in a direction toward each other, and of the supporting arm in an opposite direction to prevent the harness from being thrown or dropped therefrom when the latter gravitates to a released position.

With these and other objects in view which will appear as the nature of the invention is better understood, the same consists in the combination and arrangement of parts hereinafter more fully described.

In the drawing forming a part of this application and in which like numerals of reference indicate similar parts in the several views: Figure 1 is a perspective view. Fig. 2 is a side elevation with the parts in section, the supporting arm being shown in open position by dotted lines. Fig. 3 is a section taken on line *a—a* of Fig. 1, and looking in the direction of the free ends of the arms. Fig. 4 is a detail view of the outer end of one of the arms.

The device may be constructed from any suitable material and comprises a bracket 5, including a base 6 of any suitable form but as shown in the present instance as being substantially rectangular in contour. The

base is provided with suitable openings 7 for the reception of the fastening elements 8 by means of which the device is fastened on the wall of a stable, stall or other suitable support. Projecting from adjacent the upper and lower ends of the base are spaced pairs of pivot lugs 9 and 10 which may be formed integral with the base or otherwise suitably secured thereto.

Pivotedly mounted between the lugs for vertical swinging movement are oppositely curved arms 11 and 12. Each of the arms have their ends adjacent their pivots provided with a perfectly flat surface or shoulder 13 adapted to abut against the base 6 to limit the movement of said arms in a direction toward each other, and to further support the arm 11 normally in horizontal position. The free end of the arm 11 is curved inwardly as at 14 and provided with a recess or pocket 15 adapted to receive the hook like terminals 17 of the arm 12, and has a bottom 18 and side walls 19, the latter serving to prevent the arms from being casually disconnected when in operative position by animals passing by and bearing against the harness or by any other lateral pressure which may be brought to bear against the sides of the device. The upper surface 20 of the hook like portions 17 is beveled or inclined so as to slide freely over the curved surface 14 of the arm 11 when raised to operative position, thus causing the arm 11 to move outwardly and upwardly until the hook like portion 17 passes the end of the arm 11 after which the said hook like portion 17 will gravitate into the pocket or recess 15 thereby automatically interlocking the arms in operative or supporting position.

The device is extremely simple and readily and easily manipulated. The harness when not in use is placed upon the curved arm 10 after which the latter is moved upwardly in interlocking engagement automatically with the arm 11 in the manner hereinabove stated, whereby the harness will be supported in suspended position. When it is desired to use the harness the arm 11 is raised slightly by means of the handle 21 which may be formed integrally therewith or otherwise secured thereto, thus disconnecting the free ends of the arms and permitting the arm 10 to gravitate to released or open position from which the harness may be easily removed. By reason of the connection between the

arms, it will be manifest that the heavier the harness the more effective the arms will be held in interlocking engagement.

With a view of limiting the movement of the arm 10 to prevent the harness from being thrown therefrom on movement of the arm to released or open position, I employ a stop lug 22 located immediately below the arm 10 and having its upper surface beveled 10 as at 23 to accommodate the curvature of the arms.

From the foregoing description taken in connection with the accompanying drawing, it is believed that the nature and advantages of the invention will be perfectly clear, without further explanation and therefore the same has been omitted. However I desire to have it understood that while I have shown and described the preferred form of 20 my invention I am not to be limited to this particular construction and arrangement of parts as various changes may be made within the scope of the appended claims without departing from the spirit or sacrificing any of the advantages of the invention.

What I claim is:

1. In a device of the class described, a base, a pair of oppositely movable arms 30 freely pivoted on said base for independent vertically swinging movement, means for supporting one of said arms normally horizontal, said arms being adapted for automatic interlocking engagement with each 15 other on movement of the other of said arms to operative position.

2. In a device of the class described, a base, a pair of oppositely movable arms

freely pivoted on said base for independent vertical swinging movement and having 40 their free ends interlocked in operative position, means for supporting one of said arms normally horizontal, and means for lifting said arms to permit the other of said arms to gravitate to inoperative position.

3. In a device of the class described, a base, a pair of pivotally movable arms freely pivoted on said base and having their 50 free ends interlocked in operative position, means for slightly tilting one of said arms whereby the other of said arms gravitates to an inoperative position, and means for limiting the movement of the latter mentioned arm on its movement to an inoperative position.

4. In a device of the class described, a base, a pair of oppositely movable arms freely pivoted on said base for vertical swinging movement, one of said arms having its free end extended inwardly and formed to provide a pocket, and the other of said arms terminating in a hook adapted to be positioned in said pocket when said arms are operatively associated, and the side 65 walls of said pocket being adapted to prevent casual separation of the arms when lateral pressure is brought to bear against the sides thereof.

In testimony whereof I affix my signature 70 in presence of two witnesses.

ELMER E. GOAR.
